AUTOMATIC SPACE CLOSURE FOR DOORS

Walter J. McGarr, Cordele, Ga.

Application November 9, 1932, Serial No. 641,905

6 Claims. (Cl. 20—16)

My invention relates to improvements in automatic space closures for doors, windows and the like, and it consists in the combinations, constructions and arrangements herein described and claimed.

An object of my invention is to provide means for closing the space between hinged doors or windows, such as French doors, accordion doors, etc., to obviate the necessity of future adjustments on account of shrinking or swelling of the doors.

A further object of my invention is to provide a device for automatically closing the space between the doors, which will serve as a metal weather-strip, thus preventing drafts which might otherwise take place without such closure.

A further object of my invention is to provide an automatic closure which is applicable to old work as well as new work, which can be installed quickly and at little expense.

Other objects and advantages will appear in the following specification and the novel features of the invention will be particularly pointed out in the appended claims.

My invention is illustrated in the accompanying drawing forming part of this application, in which:

Figure 1 is a front view showing a set of folding doors to which my invention is applicable.

Figure 2 is an enlarged section along the line 2—2 of Fig. 1, looking in the direction of the arrows.

Figure 3 is a section similar to Fig. 2, but showing the doors in open position about to be closed, and,

Figure 4 is a perspective view of a base plate used in my construction.

In carrying out my invention I may make use of folding doors, such as those shown in Fig. 1, or single doors, since the principle is the same in both instances. In Fig. 1, I have shown a set of folding doors indicated at 5, 6, 7 and 8, respectively. The doors 5 and 6 are hinged together at 9 and the doors 7 and 8 at 10. The door 5 is hinged to the jamb 11 by hinges 12 and the door 8 is hinged to the jamb 13 by hinges 14. The description thus far applies to doors in ordinary use.

I make use of a plate 15 such as that shown in Fig. 4. This plate has a flange 16 at right angles thereto and is provided with a curved leaf spring 17 which is secured to the plate at 18. It has on one side thereof guide cylinders 19 shown in dotted lines in Fig. 4 and in full lines in Figs. 2 and 3. While I have shown the

plate 15 as having two of these cylinders, it will be understood that this plate may be considerably longer and may be provided with other guide cylinders and springs similar to those shown in Fig. 4.

The plate 15 is of a width substantially the same as the thickness of the door. It will be seen from Figs. 2 and 3 that the plate 15 is secured to the door 6 by means of screws such as those shown at 6', so that the larger dimension of the plate is flush against the forward edge of the door.

The door 6 is provided with a bore 21 to receive the guide cylinder 19. A rod 22 is provided with a head 23 at one end and at the other end is fastened to a plate 24 which is designed to extend the full height of the door, and which has a flange portion 25, preferably V-shape in cross section, the edge of this flange portion being arranged to slide on the flange 16. An abutment strip 26 is secured to the door 6.

An anti-friction member is provided for the door 7. This consists of an L-shaped metal plate 27 which is secured by screws 27' to the corner of the door. The plate 27 is recessed to receive a roller or wheel 28 which is journalled on an axle 29 carried by the plate 27. The wheel 28 is disposed partly in a recess 30 in the corner of the door 7. There may be a number of these rollers at different places on the door, but they are all made like that shown in figures.

Consider Figure 3. When the door 7 is swung toward the door 6, the roller 28 will engage the inclined surface of the flange 25 and will tend to force the plate 24 toward the plate 15. The guide rod 23 will move from the position shown in Fig. 3 to that shown in Fig. 2, and the outer edge of the V-shaped flange 25 will ride along the flange 16 of the plate 15. The parts, when the doors are shut, will be in the position shown in Fig. 2. In this position it will be observed that the space between the doors is bridged by the V-shaped flange member 25 which will thus prevent drafts and will also make a finished appearance on the inner side of the door. That is to say, it will cover the crack.

If the doors 7 or 6, or in fact, any of the doors shown in the folding door arrangement, should shrink, tending to draw away, the plate 24 would be moved by the spring 17 to outer position, i. e., 105 against the edge of the door 7, so that there may be considerable space between the edges of the doors 6 and 7, and this space will be always covered by the automatic closure mechanism. The installation of this device can be readily made.

The rods 23 are preferably connected to the plate 24 by riveting thereto, and the stop member or head 23 which limits the outward movement of the plate 24 may be screwed to the rod or fastened in any other suitable way.

For a single door, the construction would be substantially the same, the door 6 in that instance being replaced by the jamb and the plate 15 being screwed to it in precisely the same manner as shown in Figs. 2 and 3 of the drawing.

The member 24 may be drilled to receive the bolt of the lock just as the keeper is, that usually come with the locks.

I claim:

1. The combination with a pair of swinging doors, of a movable plate carried by one of said doors, said plate having a flange arranged to bear on the side of the door in all positions of the plate, spring means carried by the door for maintaining the plate in an outer position, said flange being arranged for engagement by the companion door in its swinging movement to force the plate toward the first named door.

2. The combination with a pair of hinged doors, of a flat closure plate, a guide member carried by one of said doors, a rod secured to said plate and arranged to slide in said guide member, a spring for normally holding said plate away from said door, said plate having a cam flange extending from the bottom to the top of the door and having one edge in contact with the side of the door, the cam portion of the flange being normally in position to be engaged by the other door to force said plate toward the first named door and to permit the plate to contact with the opposed edge of said second named door when the doors are in closed position.

3. The combination with a pair of swinging doors, of an abutment carried by one door and projecting beyond the end thereof, a plate having a flanged portion secured to the abutment-carrying door, a guide member carried by said plate, a closure member, a rod secured to said closure member and extending through said guide, said closure member comprising a flat plate having a flange bridging the space between the plates, the edge of the flange being arranged to bear on the flange of the first named plate, a spring between said plates for normally forcing them apart, said bridging flange being normally in position to be engaged by the other swinging door to force the closure plate toward the first named plate and to permit the flat portion of the closure plate to abut the opposing edge of the second named door when the latter is in engagement with the abutment.

4. The combination with a pair of swinging

doors, one of said doors having a recess, of a flat plate extending across the front edge of the recessed door, said plate having a laterally extending flange secured to the side of the door, a guide member carried by said plate and arranged to enter said recess, a guide rod slidable in said guide member, a closure member secured to said guide rod, a spring secured to said first named plate and arranged to bear on said closure member, said closure member comprising a flat body portion having a V-shaped flange, the edge of said V-shaped flange being arranged to bear at all times on the flange of the first named plate, an abutment member carried by said door and an anti-friction member carried at the corner of said second named door, said closure plate being normally in position to be engaged by said anti-friction member to force said closure plate toward said first named plate and to bring the edge of the door into parallelism with the flat portion of the closure plate when the second named door is against the abutment.

5. The combination with a pair of doors, one of said doors having a recess extending inwardly from the end thereof, a flat plate carried by said recessed door, said plate having a laterally extending flange arranged to be secured to the side of the door, an abutment member carried by said door on the opposite side, a guide member secured to said plate and arranged to extend into said recess, a guide rod extending through said guide member and being provided with a stop member disposed in said recess, a closure member secured to said guide rod, a spring secured to said plate and arranged to bear on said closure member, said closure member comprising a flat portion and a V-shaped flange having an edge arranged to bear on the flange of said first named plate, the second door having secured at a corner thereof a wheel bearing plate, a wheel rotatably mounted in said wheel bearing plate and arranged to engage the said V-shaped flange for forcing said closure plate toward the first named door against the tension of the spring, the edge of the second named door being parallel with and abutting the flat portion of the closure plate when the second named door is against the abutment.

6. In combination, a support, a swinging door, a movable plate carried by said support and having a cam flange extending from the bottom to the top of the support and arranged to bear on one face of said support at all times, spring means carried by the support for maintaining the plate in an outer position, said flange being arranged for engagement by the door in its swinging movement to force the plate toward the support.

WALTER J. McGARR.
